UNITED STATES PATENT OFFICE.

LUTHER D. LOVEKIN, OF PHILADELPHIA, PENNSYLVANIA, ASSIGNOR TO THE LOVEKIN WATER HEATER COMPANY, OF PHILADELPHIA, PENNSYLVANIA, A FIRM COMPOSED OF MARGARET J. FOWLER, J. SCOTT FOWLER, AND PHILLIP D. FOWLER.

THERMOSTATIC GAS-VALVE CONTROL.

1,381,652.

Specification of Letters Patent. Patented June 14, 1921.

Application filed May 22, 1917. Serial No. 170,155.

To all whom it may concern:

Be it known that I, LUTHER D. LOVEKIN, a citizen of the United States, residing at 6320 Drexel road, Philadelphia, in the county of 5 Philadelphia and State of Pennsylvania, have invented a certain new and useful Thermostatic Gas-Valve Control, of which the following is a specification.

My invention relates to apparatus for 10 automatically controlling the gas supply to a boiler-heating burner.

The purpose of my invention is to obtain direct effective connection of a preferably long-movement snap-action valve opening 15 and closure mechanism with the thermal element which operates it, without the lost motion of intermediate connecting and movement-multiplying devices.

A further purpose of my invention is to 20 connect a snap-action valve operating mechanism to a thermal element by an adjustment extensible in the direction of movement and guarding the operating mechanism from improper change of adjustment except when 25 removed from the casing.

A further purpose of my invention is to provide a thermal operating mechanism for 30 a snap-action valve opening and closing mechanism with a position adjustment and a pressure adjustment in direct line with each other.

Further purposes will appear in the specifications and in the claims thereof.

I have preferred to illustrate my invention 35 by but one form thereof, selecting therefor a form which has proved in use to be practical, efficient and reliable, and which at the same time well illustrates the principles of my invention.

40 Figure 1 is a side elevation of this preferred form of my invention applied to a water heater.

Fig. 2 is a longitudinal section through the regulating mechanism shown in Fig. 1.

45 Fig. 3 is a side elevation, partly sectioned, showing the structure of Fig. 2 with the valve in a different position.

Figs. 4, 5 and 6 are sections of Fig. 3 taken upon lines 4-4, 5-5 and 6-6 re- 50 spectively.

In the drawings, similar numerals indicate like parts.

My invention is applicable to a gas heat-

ing unit or assemblage for homes and comprises a boiler 7, heater 8 and regulating mechanism connected with the heater by pipe 10. The regulating mechanism comprises a long stroke, preferably bellows-type of thermostatic element loosening the expansive forces of gas, symbolized by that known in 60 the trade as a "sylphon" thermal element 11, a tube 12, hermetically connected therewith, and introduced within the boiler, gas inlet valve 13, adapted to engage seat 14, and intermediate valve-operating mechanism. 65

The actual throwing of the valve is accomplished by pressure of one or other of the faces 15, 16 of a nose 17 against one of the faces 18, 19 upon the wedge end 20 of a lever 21 pivoted at 22 and carrying the valve at 70 its opposite end. The lever is supported by a bracket 23 and is pivotally connected with the valve stem 24. Upon the opposite side of the valve the stem is secured to the valve by a nut 25 and passes through a guide 26. 75

The nose 17 is carried by an arm 27 pivoted at 28 to a lug 29 moved by the sylphon element. A spring 30 secured to the end 31 of the lever and to a post 32 keeps the nose 17 constantly pressing against one or the other of the faces upon the end of the lever. 80

The post may be adjusted by means of the thread 33 and is locked in adjusted position by the nut 34, permitting variation in the extent of opening of the valve. 85

The lug 29 is rigidly connected with a rod 35 which is threaded into a fitting 36 upon the lower side of the sylphon thermal element. With expansion and contraction of the thermal element the rod 35 is moved longitudinally, in which movement it is guided against lateral displacement by the engagement of a disk or disks 37, 38 with the wall 39 of a cylindrical passage; and rotation of the rod is prevented by guides 40 upon opposite sides of the lug 29. 90

Movement of the sylphon element is resisted by a compression spring 41 bearing conveniently against disk 38 upon the rod 35, at one end, and against a head 42 upon a screw at the other. The screw can be adjusted to vary the degree of compression of the spring, and is locked in adjusted position by the nut 44. 100

The gas inlet is shown at 45 and the outlet 105 for pilot light supply is shown at 46.

The sylphon element is contained in a chamber 47 in line with the rod 35. The top of this chamber is closed by a removable cap 48, permitting withdrawal of the thermal element, rod and lever when the spring 30 has been detached from the arm 27. The casing is also separable in approximate line with the valve between flanges 49 and 50. An opening 51 is provided for convenient 10 observation of the valve operation and access thereto.

In assemblage, the sylphon element and tube are connected with the rod 35, carrying arm 27, before insertion. The spring 41 is 15 placed in the lower part of the casing and the valve and valve lever are mounted upon it. The stop and tension spring 30 for lever 27 are put in place in the upper part of the casing. The sylphon element, rod and lever 20 27 are then inserted and the spring 30 is secured to the lever, the lower part of the casing being conveniently attached last. The opening in the side of the casing permits observation of trial working of the 25 valve and exact preliminary adjustment of the position of the other parts when snap action occurs, but without separation of the casing parts.

In operation: From the position shown 30 in Fig. 2, corresponding to relatively cool boiler water and a contracted sylphon element, expansion of the sylphon element causes downward movement of rod 35 and arm 27 with consequent downward travel 35 of nose face 15 along the wedge face 18 of lever 21 stretching the spring 30 and compressing spring 41 until the nose 17 passes the point at which the faces 18 and 19 meet. Immediately, the action of the spring 30 40 causes the opposite face 16 of nose 17 to slide upon wedge face 19 of the wedge end 20 of the valve lever throwing this lever quickly and to its full stroke to close the valve. The valve is maintained in closed 45 position, by reason of continued pressure of the nose 17 upon the surface 19, throughout any further downward movement of the sylphon element and through partial upward movement thereof, the parts being in the position shown in Fig. 3. When upward movement 50 of the sylphon element causes the nose 17 to pass the point of the wedge end 20 of the lever 21, the valve is snapped open by a corresponding full-stroke operation 55 and is maintained in open position, as seen in Fig. 2, during further upward movement 60 of the sylphon element and any subsequent downward movement thereof up to the time that nose 17 passes the point of the wedge end of lever 21.

The point of snap action with respect to the position of the sylphon element is determinable by longitudinal adjustment of spring 41 or of the rod 35 within the fitting 65 in the end of the sylphon element. Adjust-

ment of the rod may be made by withdrawing the element, rod and lever to permit the turning of the rod by one or more complete turns in either direction according to the adjustment desired. The necessity for 70 withdrawal to effect this adjustment affords protection against accidental or unauthorized change in the adjustment.

The range of temperature change for a given movement of spring 41 and the temperatures at which the valve will close or open are capable of adjustment by tightening or releasing the spring 41. This enables the user to set the temperature of water 75 to be maintained in the boiler, and gives a wide range of temperatures. To secure hotter water, the user merely tightens the spring 41.

It will be noted that adjustment of the rod 35 either upwardly or downwardly will 85 require corresponding adjustment of the spring, if the same range of expansion of the thermal element for a given temperature range is to be maintained.

It will be evident that various changes 90 may be made in the form of the invention within the scope of my claims while still obtaining the advantage of my invention as disclosed herein.

Having thus described my invention, 95 what I claim as new and desire to secure by Letters Patent, is:—

1. In an automatic gas regulator, a thermostatic element, a rod longitudinally adjustable with respect to said element, an 100 arm pivotally connected to said rod, means for adjusting the position of the arm longitudinally with respect to the element, a spring normally moving said arm transversely with respect to the rod length, a 105 nose or abutment on said arm and a snap-action valve closure operated by said nose.

2. In an automatic gas regulator, a thermostatic element, a rod rigidly connected to and longitudinally adjustable with respect to said element, a retarding spring in line with the said rod, a compression adjustment for said spring and a snap-action valve-operating mechanism including a lever free from engagement with said retarding 110 spring and carried by said rod, said mechanism being adjustable as to range and critical temperature by the adjustment of the rod and the spring.

3. In an automatic gas regulator, a thermostatic element, a rod extending longitudinally thereof, and adjustable longitudinally with respect thereto, a compression spring resisting movement of said element and rod, an arm mounted upon and pivotally connected at one end with said rod and longitudinally movable therewith, a spring adapted to draw the other end of said arm away from said rod, a nose on said arm, a valve-operating lever pivoted at its center 115 120 125 130

and having oppositely sloping faces engaged by said nose and a valve operated by the lever.

4. In an automatic gas regulator, a thermostatic element, a rod extending longitudinally thereof, a compression spring resisting movement of said element and rod, an arm mounted upon and pivotally connected at one end with said rod and longitudinally

movable therewith, a spring adapted to draw 10 the other end of said arm away from said rod, a nose on said arm, a valve-operating lever pivoted at its center and having oppositely sloping faces engaged by said nose and separate longitudinal adjustments for 15 said rod and said spring.

LUTHER D. LOVEKIN.
